DESIGN FOR A LEVER TYPE SCREW DRIVER

Samuel Bloomfield, Wichita, Kans., assignor to
C. Earl Hovey, Kansas City, Mo., as trustee

Application June 25, 1945, Serial No. 120,330

Term of patent 14 years

(Cl. D54—13)

To all whom it may concern:

Be it known that I, Samuel Bloomfield, a citizen of the United States, residing at Wichita, in the county of Sedgwick and State of Kansas, have invented a new, original, and ornamental Design for a Lever Type Screw Driver, of which the following is a specification, reference being had to the accompanying drawing, forming a part thereof.

Fig. 1 is a side elevational view of a lever type screw driver, showing my new design.

Fig. 2 is a top plan view thereof; and

Fig. 3 is a perspective view thereof, in open condition.

I claim:

The ornamental design for a lever type screw driver, as shown.

SAMUEL BLOOMFIELD.
